UNITED STATES PATENT OFFICE.

JOHN HERMANS, OF VANCOUVER, WASHINGTON.

HEATING FURNACE.

Application filed November 12, 1925. Serial No. 68,675.

This invention relates to improvements in heating furnaces, and it consists in the constructions, combinations and arrangements herein described and claimed.

5 An object of the invention is to provide a furnace intended particularly for heating residences (although not confined to such use), one of the advantageous features consisting of building a plurality of flues in the vicinity of the fire chamber out of brick or the like, the flue walls giving off considerable heat for a considerable length of time even after the fire has gone out.

10 Another object of the invention is to provide a one-pipe furnace consisting of the combination of certain metallic jackets and a central brick core having a plurality of flues through which the products of combustion circulate before passing on to the chimney with the result that the brick core becomes very hot and in turn heats the air in said jackets.

15 Other objects and advantages appear in the following specification, reference being had to the accompanying drawings, in which—

Figure 1 is a partial front elevation and vertical section of the improved furnace.

20 Figure 2 is a central vertical section of the furnace taken substantially on the line 2—2 of Figure 3.

25 Figure 3 is a horizontal section taken on the line 3—3 of Figure 2.

30 Figure 4 is a horizontal section taken on the line 4—4 of Figure 2.

35 In carrying out the invention, provision is made of outer and inner metallic jackets or casings 1 and 2 which are in spaced relationship to provide a passage 3 for the down flow of cool air as indicated by the arrows. Both jackets have conical shoulders 4 and 5 which respectively terminate in collars 6 and 7. The collars end at a grate 8 in the floor 9 of the residence or other place intended 40 to be heated. The hot air passes upwardly out of the inner jacket at the center of the grate and the cool air returns at the edges of the grate into the passage 3 mentioned before.

45 50 A cement base 10, metallic ring or the like provides an appropriate support for the outer jacket 1. The inner jacket 2 is shorter than the outer jacket, falling short of the bottom as indicated at 11 in Figure 1. This arrangement produces a continuation of the passage 3 so that there may be communica-

tion between the jackets. But the inner jacket 2 is adequately supported by a plurality of brackets 12 (Figs. 2, 3 and 4) which are built into the brick core 13 and in turn are supported by ledges 14 (Fig. 2) projecting from the brick core.

The core, generally designated 13, is built of bricks and in the construction thereof is made to include the fire chamber 14^a with 65 which the main central flue 15 communicates. It is into this flue that the products of combustion originating in the fire chamber 14^a are discharged whereupon they pass into a common flue chamber 16 from which a 70 plurality of flues 17 extend in the downward direction. These flues are substantially upright, and in Fig. 3 are seen to pass around the fire chamber 14^a so that the products of combustion may pass into the lower common 75 flue chamber 18.

This chamber, as is seen in Figure 4, has the substantial shape of a cross, the particular configuration being best adapted to the various flues that combine therewith. The 80 various upright flues 17 combine at the two members 19 of the cross, the remaining member 20 of the cross having communication with the discharge flue 21 which directs the products of combustion to the chimney pipe 85 22. The arrangement provides for a common outlet of all of the flues 17 into the cross channel 19 (Fig. 4). A door and passage 23 and 24 permit cleaning out of the lower common flue chamber 18 or in other words, 90 the cross shown in Figure 4.

A steel drum 25 is in direct communication with the main central flue 15 and the common flue chamber 16 (Fig. 2) and therefore directly receives the products of combustion when in the hottest condition. This drum includes a flange 26 by means of which it is firmly incorporated in the brick construction of the core 13. The drum is obviously closed at the upper end and although 95 herein shown as of flaring shape may in practice be of other shape. But regardless of shape, the drum is intended to extend into the air chamber 27 formed between the inner jacket 2 and the brick core 13. The disposition of the steel drum permits a quick 100 radiation of heat so that the effect of a fire in the chamber 14^a is directly felt in the room above.

105 A door 28, carried by a cast iron frame 29, 110 provides the necessary closure for the fire chamber 14^a. The customary grate of the

fire chamber is omitted in the drawings the furnace being a wood burner. The chain 30 at once controls the fire door draft opening 31 and the chimney pipe damper 32. 5 The chain is trained over pulleys 33. The arrangement may be on any known order and has no direct bearing on the invention. Metallic plates 34 are incorporated in the brick construction of the core 13 wherever 10 necessary, in order to properly support the various arches. It is observed in Figure 1 that a deflector 35 serves to direct the down flowing products of combustion toward the center of the lower common flue chamber 18. 15 There will be a similar deflector on the opposite side.

The operation of the improved furnace is readily understood. The hot products of combustion passing upwardly in the central 20 flue 15 fills the steel drum 25 and causes immediate heating of the air in the flue chamber 27. The full benefit of the fire is got before the products of combustion turn and pass downwardly in the upright flues 17. 25 Upon passing downwardly in these flues the products of combustion reach the lower common flue chamber 18, finally passing upwardly in the discharge flue 21 and off at the chimney pipe 22.

30 During the circulation of the products of combustion through the flues 15, 17 and 21, as well as the chambers 16 and 18 the surrounding brick walls become very hot. Inasmuch as the brick core is well confined 35 by the double jackets 1 and 2 the heating of the air in the chamber 27 is done most effectively. The heat in the brick walls is communicated to the air in the chamber 27 for a considerable length of time even after 40 the fire in the chamber 14^a has gone out.

The steel drum 25 performs an important function in the operation of the furnace. Assuming that the furnace is cold, a fire 45 when first built in the chamber 14^a will produce an immediate heating of the drum 25, this in turn will cause an immediate heating of the air in the chamber 27 so that this air passes upwardly in the central part of the grate 8, thereby drawing up the air in 50 the space surrounding the core and starting a circulation of air around the inner jacket 2 which continues until the furnace again becomes cold.

55 While the construction and arrangement of the improved heating furnace is that of a generally preferred form, obviously modifications and changes may be made without departing from the spirit of the invention or the scope of the claims.

60 I claim:—

1. A furnace comprising a core having a fire chamber, a jacket spaced around the core defining an air chamber above the core and having an air outlet, and a metallic drum in which the hottest products of com-

bustion from the fire chamber circulate before returning in the direction of the fire chamber, said drum extending into the air chamber and insuring quick heating of the air therein. 70

2. A furnace comprising a brick core having a fire chamber and a central flue communicating therewith, a common flue chamber into which said central flue discharges, a plurality of upright flues built into the 75 core and distributed around the fire chamber, said flues extending downwardly from the common flue chamber past the fire chamber, a lower common flue chamber located beneath the fire chamber into which the upright flues discharge, and a discharge flue leading from the lower flue chamber, the aforesaid various flues and chambers permitting a thorough heating of the core from the interior; and a plurality of spaced 80 metallic jackets defining a passage between themselves and a chamber around the core and directing air toward the core so that it is heated during passage over the core. 85

3. A furnace comprising a brick core having a fire chamber and a central flue communicating therewith, a common flue chamber into which said central flue discharges, said chamber having a plurality of upright flues extending downwardly past the fire chamber, a lower common flue chamber into which the upright flues discharge, a discharge flue with which a chimney pipe is communicable, the aforesaid various flues and chambers permitting a thorough heating 95 of the core from the interior; a plurality of spaced metallic jackets defining a passage between themselves and a chamber around the core and directing air toward the core so that it is heated during passage 100 over the core, and a metallic drum incorporated in the core receiving the hottest products of combustion from said central flue and first common flue chamber, the upper end of said drum being closed but extending into the surrounding air chamber to intensely heat the surrounding air and start the circulation in the jacket passages. 105

4. A furnace comprising a brick core having a fire chamber and a plurality of flues for the circulation of products of combustion from the fire chamber and heating of the cores, a plurality of spaced jackets surrounding the core for directing air past the core thereby to be heated, and a metallic 115 drum extending into the air space defined by the innermost jacket at the top of the core, receiving the hottest products of combustion from the fire chamber thereby immediately heating the air surrounding said drum to start a circulation in the chambers defined by said jackets. 125

5. A furnace having a brick core, a fire chamber in said brick core, a flue chamber and a main central flue furnishing commun- 130

- cation between said chamber and the fire chamber, a plurality of upright flues extending downwardly from said flue chamber, a lower common flue chamber into which
5 said upright flues discharge, said upright flues having deflectors for directing the products of combustion into said lower common flue chamber, a discharge flue leading from the lower common flue chamber, outer
10 and inner jackets spaced in respect to each other and in respect to the brick core, the inner jacket being shorter than the outer so that air may pass from one to the other for contact with the brick core, and a metallic
15 drum incorporated in the core and extending into the air space adjacent to the top of the brick core thereby producing a heating of the immediately surrounding air and starting a circulation in the spaces defined by said jackets. 20
6. A furnace comprising an internally heated brick core, an outer jacket closed at the bottom, an inner jacket in spaced relationship to both the outer jacket and the core, thereby defining air passages and an air chamber, said inner jacket being shorter than the outer jacket, a plurality of brackets built into the brick core supporting the inner short jacket at the lower end, and ledges built out from the core providing a support 25 for said brackets. 30

JOHN HERMANS.
